UNITED STATES PATENT OFFICE

HARRY A. ATWATER, OF KANSAS CITY, MISSOURI

AIR PREHEATING CONSTRUCTION FOR FURNACES

Application filed July 10, 1929. Serial No. 377,263.

This invention relates to furnace construction, and aims to provide improved features in the arrangement and construction of the passages through which the air is conducted to the combustion chamber, with a view to effecting a more uniform and efficient pre-heating of the air required for furnaces.

Accordingly, the invention comprises an air pre-heating construction having provision for sub-dividing the air flow into more or less separate or independent currents, by means of a partition structure which serves not only to split up the incoming air into a plurality of streams all flowing in the same direction, but also to subject the air to extensive pre-heating areas which are maintained heated by conduction from the floor of the combustion chamber.

The invention further comprises a pre-heating structure which is economical and comparatively easy to assemble and adapted to maintain its structural position and shape without material variation due to temperature changes.

With the foregoing general objects in view, the invention will now be described by reference to the accompanying drawings illustrating one type of construction which I have devised for embodying the improvements in practical form, after which the various features and combinations deemed to be novel will be particularly set forth and claimed.

In the drawings—

Figure 1 is a horizontal sectional view showing a furnace structure embodying the present improvements, and representing a section taken on the line I—I of Figure 2, with portions broken away;

Figure 2 is a vertical transverse sectional view, representing a section taken on the line II—II of Figure 1;

Figure 3 is a vertical longitudinal sectional view, representing a section taken on the line III—III of Figure 1; and

Figure 4 is a perspective view, on a larger scale, illustrating one of the units of the partition structure and two adjoining floor sections prior to their assembly.

The invention as illustrated by the drawings involves various features of improve-

ments over the furnace construction covered by Letters Patent No. 1,573,507 granted to me on Feb. 16, 1926, while retaining all of the advantageous features of the patent. As illustrated in the patent, the incoming air was intercepted by vertical transverse partitions having openings operating to split up the air flow into a plurality of minor streams all moving in the same direction, but certain disadvantages of this construction lay in the partial obstruction of the air flow due to the area of the partitions, and in the fact that the greater portion of the heating effect was dependent upon the action of the steel cover or floor plates forming the roof or ceiling of the pre-heating passages.

While various expedients might be resorted to for increasing the rate of heat transfer from the combustion chamber for pre-heating the air, most of these are found to offer various objections, such as obstructing the air flow by cutting down the cross-sectional area of the air passage and hence the feeding capacity thereof, such as would be the result of any transverse partition structure; likewise, the friction introduced by such type of structure; the dirt and refuse collecting tendency of any available horizontal partitioning elements that might be used, which is characteristic of tube assemblies often employed for heating effects, whereas such tube elements also interpose an excessive degree of friction, retarding the flow and reducing the capacity with corresponding draft losses; and further, the difficulty of satisfactorily and efficiently supporting such assemblies at all necessary points without buckling or any malformation of the steel parts composing them.

The present construction, therefore, aims to overcome these various objections by providing a partitioning and preheating means with as full a pre-heating effect as possible and with minimum reduction of the capacity of the air feed passages.

Referring now to the drawings in detail, these show a furnace structure comprising side walls 10 and end walls 11 of any practical type for providing a furnace combustion chamber 12. The floor of this chamber com-

prises suitable tiling 14 arranged with a gradual downward slope from what may be termed the rear wall 11 toward the opposite or front wall of the chamber 12, the support for said tiling comprising a sheet metal structure made up of longitudinal steel plates 15 having marginal interengaging tongue and groove flanges 16, 17, respectively, a set of transverse supporting angles 18 carried by longitudinal angle members 19 providing a framework for the support of the steel plates 15 and the tiling comprising the floor structure.

As in the patent referred to, this arrangement provides a floor construction which readily transmits heat from the chamber 12 to the space beneath the floor for pre-heating the air on its way to said chamber, and at the same time affords a liquid tight flooring to prevent any liquid fuel (where such fuel is used) from leaking through, and the slope of the floor promotes proper drainage of any excess or unburnt fuel from the combustion chamber. For such drainage, a channel or trough 20 is provided surrounding the air feed opening 22 through the floor beneath the burner compartment 23 formed by the arch 24, and leading to an outlet pipe 26.

For pre-heating the air supplied the combustion chamber, the space beneath the floor of said chamber is partitioned to form air-feed passages similarly arranged at the opposite sides of the middle longitudinal line of the furnace, the partitioning structure including longitudinal metal sheets or plates 30 suitably positioned and secured for forming intake passages 31 communicating at their front ends with the air intake openings 32 (provided in the front wall 11 of the furnace structure) and at their rear ends with a transverse passage 33, from which a return pre-heating passage 34 is formed between said partition sheets or plates 30 leading to the floor opening 34, through which the air is discharged into the burner compartment 23.

By this means, the incoming air is caused to pursue a course, as indicated by the arrows in Figure 1, from the openings 32, through the passages 31, 33 and 34, during which course the air is subjected to the pre-heating effect of successively and increasingly hotter portions of the bottom face of the furnace combustion chamber, as explained in my previous patent referred to.

In order to further subdivide or split up the incoming air and to promote the pre-heating action, vertical sheets 36 having a combined pre-heating and partitioning function, are arranged in longitudinal and spaced relation within the passages 31 and 34, the upper margins of these sheets 36 being formed with rolled flanges 37 adapted to be interengaged between the tongue and groove flanges 16, 17, of the cover sheets or plates 15, as clearly represented in Figures 2 and 4. The lower

edges of the sheets 36 are formed with lateral stiffening flanges 38 for which spaced notches 40 are provided in transverse angle member 41 extending across the lower portions of the passages 31 and 34, as shown in Figures 1 and 2. In order to facilitate the assembly of the vertical sheets 36, their upper margins are cut away sufficiently, as indicated at 42, to clear the upper transverse angles 18 and permit insertion of the sheets 36 into engaged relation with the flanges 16 of the cover sheets 15, and then dropping of the sheets 36 to seat their bottom flanged portions 38 into the notches 40 of the angle members 41 comprising the underframe. Thus the liquid tight character of the joints between the cover sheets 15 is preserved by this method of mounting and attaching the partition sheets 36, the latter serving to divide the space within each of said passages 31 and 34 into a plurality of separate longitudinal and relatively small passages with a minimum of obstruction to the air flow, and accordingly, increased area of pre-heating surface. An extended intimate contact is made between the hot cover sheets and the partitioning sheets, whereby the conduction of heat throughout the latter is promoted. In this connection, it may also be noted that the type of joint or seam connecting the sheets 15 and 36, retains all the structural stiffness of the channel shape design while permitting all necessary compensating action due to temperature changes, the only fastenings employed being at the front ends of the sheets 15 where bolts 45 are used for securing said ends to rigid frame pieces 46 provided with the slots 47 for said bolts (see Figure 1).

A pre-heater construction is thus provided which not only preserves all the advantages of my previous construction, such as temperature compensating, leak-proof and air-tight joints, and efficient drainage, but important new advantages are secured in the way of more efficient pre-heating action. It is found that the provision of series of longitudinal partition sheets brings about the desired effect of both splitting up the flow of air into a multiplicity of thin streams or currents of air and of spreading these streams of air over a maximum heating surface as presented by both sides of the partitions or pre-heating sheets, in which a maximum flow of heat by conduction has been established by virtue of their intimate connection throughout their upper margins with the seams between the hot cover sheets 15. The amount or extent of pre-heating surface may be varied according to conditions, by increasing or diminishing the number of said partitions, and correspondingly varying the size of the air passages. Since there are no horizontally arranged heat transfer surfaces employed, no obstruction is offered to the air flow, and the full cross-sectional area of the air passages is

utilized as far as possible, with the minimum frictional resistance to the movement of the air, and hence with a minimum of draft loss through the pre-heater. The collection of 5 dirt and refuse which characterizes horizontal or tube structures is also obviated, and practically no attention is required for keeping the improved construction clear and clean in all respects.

10 The type of construction, in addition to its being free to compensate automatically for temperature changes, is also protected against buckling or warping tendencies, by virtue of the joint structure in the seam connections and the reinforcing flanges at the 15 bottom margins of the pre-heating sheets.

20 While I have herein illustrated and described what I have found to constitute one practical and efficient form of construction for embodying the proposed improvements, I desire to be understood as expressly reserving the right to make all such changes or modifications as may fairly fall within the scope of the following claims.

25 Having thus described my invention, what I claim and desire to secure by Letters Patent is:

30 1. A furnace construction comprising a combustion chamber having a floor, and an air-feed passage beneath said floor for conducting air from the exterior of the furnace to said chamber, and one or more metallic air pre-heating sheets suspended from said floor in position to subdivide the flow of air 35 through said passage and subject the same to the pre-heating effects of the lateral faces of said sheets.

40 2. A furnace construction comprising a combustion chamber having a floor, and an air-feed passage beneath said floor for conducting air from the exterior of the furnace to said chamber, and one or more metallic air pre-heating sheets freely suspended from said floor in longitudinal position within 45 said passage for subdividing the flow of air therein and subjecting the same to the pre-heating effect of the lateral faces of said sheets.

50 3. A furnace construction comprising a combustion chamber having a floor, and an air-feed passage beneath said floor for conducting air from the exterior of the furnace to said chamber, said floor including a metallic cover plate structure overlying said passage, and one or more metallic air pre-heating sheets suspended from said structure in 55 position to subdivide the flow of air through said passage and subject the same to the pre-heating effect of the lateral faces of said sheets.

60 4. A furnace construction comprising a combustion chamber having a floor, an air-feed passage beneath said floor for conducting air from the exterior of the furnace to said chamber, said floor including a metal-

lic cover plate structure overlying said passage, and one or more metallic air pre-heating sheets suspended from said structure in position to subdivide the flow of air through said passage and subject the same to the pre-heating effect of the lateral faces of said sheets, said plate structure and pre-heating sheets being connected and arranged for automatic compensating action in response to 70 temperature changes therein.

75 5. A furnace construction comprising a combustion chamber having a floor, an air-feed passage beneath said floor for conducting air from the exterior of the furnace to said chamber, said floor including a sectional metallic cover plate structure overlying said passage, and one or more metallic air pre-heating sheets interengaging said cover plate structure at the connecting lines of the sections thereof and suspended within said passage in position to subdivide the flow of air therein and subject the same to the pre-heating 85 effect of the lateral faces of the sheets.

80 6. A furnace construction comprising a combustion chamber having a floor, an air-feed passage beneath said floor for conducting air from the exterior of the furnace to said chamber, said floor including a sectional metallic cover plate structure overlying said passage, and one or more metallic air pre-heating sheets suspended longitudinally within said passage in position to subdivide the flow of air therein and subject the same to the pre-heating effect of the lateral faces 90 of the sheets, the upper margins of said sheets and the connected portions of said cover plate sections being formed with interengaging tongue and groove flanges providing liquid and air-tight seams along said connecting lines.

95 7. A furnace construction comprising a combustion chamber having a floor, an air-feed passage beneath said floor for conducting air from the exterior of the furnace to said chamber, said floor including a metallic cover plate structure overlying said passage, one or more metallic air pre-heating sheets suspended from said structure in position to subdivide the flow of air through said passage and subject the same to the pre-heating 100 effect of the lateral faces of said sheets, and means reinforcing the lower margins of said sheets against lateral warping or buckling while permitting longitudinal expansion or contraction of the sheets in response to temperature changes.

105 In witness whereof I hereunto affix my signature.
